WELDED BOX FRAME FOR VERTICAL INTERNAL COMBUSTION ENGINES

Friedrich Fohrer, Augsburg, Germany, assignor
to Maschinenfabrik Augsburg-Nürnberg A. G.,
Augsburg, Germany, a corporation of Germany

Application February 27, 1935, Serial No. 8,535
In Germany March 28, 1934

3 Claims. (Cl. 121—194)

This invention relates to welded box frames for vertical internal combustion engines, especially Diesel engines, of the character and type shown in Patent No. 1,969,031 granted August 5, 1934, to Maschinenfabrik Augsburg-Nürnberg, A. G., wherein the tensile strains produced by the combustion pressures inside the frame are absorbed by columns and iron ties, the arrangement being such that the columns surrounding 10 the iron ties are welded into the apertures of a plurality of wrought-iron or steel plates extending over the entire length of the engine. It has been found that the upper horizontal 15 longitudinal plate, to which the cylinder and cylinder covers are secured, is sometimes exposed to bending strains, which arise when the forces produced by the combustion pressures pass from the cylinder covers over the cover screws into the upper longitudinal plate and only from there 20 into the columns and iron ties.

In accordance with the present invention, the cylinder covers are secured to the upper longitudinal plate by means of screws or bolts, which are screwed into or which pass through projections arranged laterally on the upper ends of the columns. In this way the upper longitudinal 25 plate is kept free from bending strains which would otherwise influence the welding points in an exceptionally unfavorable manner. Consequently the desired favorable direction or passage of the longitudinal and of the transverse forces from the plate into the columns is insured. Owing to the fact that the projections lie with their upper surfaces flush against the lower surface of the longitudinal plate, all bending strains 30 are kept away from the longitudinal plate. Each of the said projections is provided with a boring to receive the cylinder cover screws, this boring if necessary being threaded.

40 A constructional example of the invention is illustrated in the accompanying drawings, wherein

Figure 1 is a side view of the upper part of an engine frame partly in longitudinal section through one of the columns of the frame,

Figure 2 is a plan of the engine frame, a portion of the upper longitudinal plate being cut away above one column, and

Fig. 3 is a sectional view on the line 3—3 of Fig. 2.

The columns 1, through which the iron ties 2 are passed, are so introduced into the upper longitudinal plate 4 with their upper ends 3 that the two lateral projections 5 of the columns 1 lie with their upper surfaces flush against the lower surface of the plate 4. In the projections 5 stud bolts 6 are screwed, by means of which the cylinders 7 and the cylinder covers 8 are secured 55 to the plate 1, the cylinders being outwardly

flanged at their upper ends and these flanges being recessed in grooves provided in the plate 4.

The vertical forces emanating from the combustion pressures are in this way easily passed over by means of the screws 6 directly into the projections 5 and from there into the columns 1, so that the plate 4 is completely freed from their load and unfavourable bending strains on the welded connection between the plate and the columns are avoided.

Having now particularly described and ascertained the nature of my said invention and in what manner the same is to be performed, I declare that what I claim is:

1. A combustion engine frame comprising a 15 series of cylinders each having a cylinder head, a connecting plate separate from said cylinders and extending transversely of the said series of cylinders for supporting the cylinder heads and with the upper side of said plate in direct supporting contact with said heads, columns extending downwardly from and welded to said plate and adapted to assume compression forces, said columns having lateral projections integral therewith and in contact with the lower side of 25 said plate, and means extending through said plate and connecting said projections directly to said cylinder heads.

2. A combustion engine frame comprising a 30 series of cylinders, a cylinder head for each cylinder, a connecting plate extending transversely of the said series of cylinders for supporting the cylinder heads and in contact with the lower sides of said heads, columns extending downwardly from said plate and adapted to assume compression forces, each column having opposed lateral projections in contact with the lower side of said plate, tension rods extending downwardly from said plate adjacent said projections, and means extending through said plate and connecting said projections directly to said cylinder heads.

3. A combustion engine frame comprising a 35 series of cylinders, a cylinder head for each cylinder, a connecting plate extending transversely of the said series of cylinders for supporting the cylinder heads and in contact with the lower sides of said heads, said plate being a part separate from said cylinders and having welded connections with said cylinders, hollow columns extending downwardly from said plate and adapted to assume compression forces, each column having lateral projections in contact with the lower side of said plate, a tension rod extending 50 downwardly from said plate in each hollow column, and means extending through said plate and connecting said projections directly to said cylinder heads.

FRIEDRICH FOHRER.
